CLAIM

The ornamental design for an outdoor mobility scooter, as shown and described.

DESCRIPTION

FIG. 1 is a perspective view of an outdoor mobility scooter showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view showing a first part of the outdoor mobility scooter in a folded state; and,

FIG. 9 is a perspective view showing a second part of the outdoor mobility scooter in the folded state, wherein the first part and the second part together form the outdoor mobility scooter.

The broken lines depict portions of the outdoor mobility scooter and form no part of the claimed design.
